UNITED STATES PATENT OFFICE.

JOHN F. MAHLSTEDT, OF LOS ANGELES, CALIFORNIA.

PRINTING-MACHINE.

1,137,157.

Specification of Letters Patent. Patented Apr. 27, 1915.

Application filed July 29, 1913. Serial No. 781,750.

To all whom it may concern:

Be it known that I, JOHN F. MAHLSTEDT, a citizen of the United States, residing at Los Angeles, in the county of Los Angeles and State of California, have invented a new and useful Printing-Machine, of which the following is a specification.

This invention relates to improvements in printing machines such as shown in a former 10 patent of mine, #1,016,756, February 6, 1912, which machine is adapted for printing letters, circulars and the like with the heading of the letter with ordinary printing ink of any preferred color, the body 15 of the letter being printed with an inked ribbon to imitate typewriting, while the signature of the letter may be printed with ink to give the effect of writing.

One object of the invention is to provide 20 for alining the sheets in a pack after being printed.

Another object is to provide paper guards 25 which may be adjusted laterally to suit the width of the paper, and which will operate to prevent the printed sheet from flying upwardly while it is being moved by the conveyer from the impression roller to the conveyer drum.

Another object is to provide means for 30 quickly shooting the printed sheet edgewise off from the end of the conveyer, thereby insuring a delivery of the sheet from the conveyer which has heretofore been uncertain on account of static electricity which 35 causes the paper to tend to stick to the conveyer.

As the machine, except for the novel features forming the present invention, is substantially similar to that shown in the said 40 former patent, I shall confine the description herein to the novel features in the present case, describing only so much of the old as may be necessary.

Referring to the drawings: Figure 1 is 45 a side elevation of the machine with a portion of the receiving table broken away. Fig. 2 is a plan view of the receiving table, a portion of which is broken away, together with a portion of the conveyer. Fig. 3 is 50 a section on line x^4-x^4 , Fig. 2. Fig. 4 is a section on line x^5-x^5 , Fig. 2.

In order to prevent the paper from flying 55 upwardly on the conveyer, I provide paper guards which comprise two blades 81 which are located above the conveyer, and may be adjusted laterally to suit the width of the

sheets being printed. Each blade 81, as shown in Fig. 4, extends into a box 82, the latter being slideable on a cross bar 83, there being a follower 84 within each box 82, 60 which is pressed against the blade 81 by a compression spring 85, thereby frictionally holding each paper guard in the desired position and permitting it to be instantly shifted laterally when desired. These 65 guards prevent the paper from flying upwardly from the conveyer.

Under certain atmospheric conditions it has been found that the sheets have a tendency to adhere to the conveyer belts on account of static electricity and to insure 70 that the sheets are delivered from the conveyer, I provide conveyer ejectors, each of which consists of an idle roller 86 rotatably mounted in a U shaped frame 87, which is 75 firmly pivoted on a rod 88 and held against lateral movement by an adjustable sleeve 89. The rollers 86 roll idly upon the top of roller 77 and act to shoot each sheet of paper 80 edgewise onto the receiving table 90.

The sheets which are received on the receiving table 90 are automatically placed in proper alinement to form a perfect stack by means of three plates 91, 92 and 93. The plate 91 is stationary, while the plates 92 85 and 93 are arranged at right angles to each other, and are caused to reciprocate, the receiving table 90 being provided with slots 94 and 95, which permit of the necessary broadside movement of the respective plates 90 92 and 93. A bar 96 is slideable on the under side of the receiving table 90, and the plate 93 is rigidly secured thereto, so that when the bar 96 reciprocates, the plate 93 will be reciprocated therewith. A bar 97 is mounted 95 to slide transversely to the bar 96, and the plate 92 is rigidly secured to the bar 97. The bar 97 is engaged by a lateral arm 98, which projects from a lever 99, which is pivoted at 100 to a bracket 101. A coil 100 spring 102 is connected to the lever 99 and to a stationary pin 103. In order to operate the lever 99, a lever 104 is employed, its upper end engaging lever 99. Lever 104 is pivoted at 105 to the frame 1, and its lower 105 end carries an offset roller 106, which is operated by a cam 107 on the gear 6, see

Fig. 1, so that as the gear 6 revolves it intermittently oscillates the lever 104, and operates the lever 99 to reciprocate the plates 110 92 and 93. These plates are so adjusted that at their inner strokes they shift each sheet

of paper edgewise into perfect alinement with the sheets which have been delivered to the receiving table, and which have in like manner been moved into alinement with each other by the reciprocating plates 92 and 93.

There is provided an ink plate 108 rotatably mounted in a manner well understood in the art on a post 116 which projects upward from a U-bar 117 extending out from the traveling bed 2. A ratchet 118, pawl lever 120, and roller 124 together with other coöperating elements, not shown, because of the nature of the views, effect rotation of the ink plate in a manner well understood in the art, and therefore not necessary to show and describe in detail herein.

What I claim is:

1. In a printing machine, printing means, a receiving table, means for delivering printed sheets from the printing means to said table, devices projecting up from said receiving table and movable against the edges of the sheets thereon, a sliding bar carrying one of said devices, another sliding bar carrying another of said devices, said sliding bars being at right angles to each other, a lever, one end of which is connected to one sliding bar, said lever having a rigid offset arm which engages and operates the other sliding bar, and means for rocking said lever.
2. In a printing machine, printing means, a receiving table, means for delivering printed sheets from the printing means to said table, devices projecting up from said

receiving table and movable against the edges of the sheets thereon, a sliding bar carrying one of said devices, another sliding bar carrying another of said devices, said sliding bars being at right angles to each other, a lever, one end of which is connected to one sliding bar, said lever having an offset arm which engages the other sliding bar, a spring connected to said lever for moving it in one direction, said printing means embracing a rotating element, a cam carried by said rotating element, a pivoted lever with one end engaging said cam, and its other end movable against the first named lever.

3. In a printing machine, printing means, a conveyer for carrying printed sheets from the printing means, a cross bar above said conveyer, boxes slidable on the cross bar, a paper guard comprising a blade extending through each box, a follower plate within each box and a compression spring between the box and follower plate acting to hold the lower portion of the box frictionally against the cross bar and to hold said plate frictionally between the cross bar and follower plate, permitting lateral movement of the blade along the cross bar and longitudinal movement of the blade with respect to the cross bar.

In testimony whereof I have hereunto set my hand at Los Angeles, California, this 16th day of July, 1913.

JOHN F. MAHLSTEDT.

In presence of—

GEO. T. HACKLEY,
LORA M. BOWERS.
